UNITED STATES PATENT OFFICE.

JOHN CORYELL, OF CORYELL, MICHIGAN.

LIFTING-JACK.

1,075,766.

Specification of Letters Patent.

Patented Oct. 14, 1913.

Application filed April 1, 1912. Serial No. 687,833.

To all whom it may concern:

Be it known that I, JOHN CORYELL, a citizen of the United States, residing at Coryell, in the county of Mackinac and State of Michigan, have invented new and useful improvements in Lifting-Jacks, of which the following is a specification.

This invention relates to lifting jacks and the object of the invention is to provide a telescoping screw jack with means whereby the head may be extended from the base with a reciprocating movement of the lever.

Further objects of this invention will appear as the following specific description is read in connection with the accompanying drawing, which forms a part of this application, and in which:-

Figure 1 is a side elevation. Fig. 2 is a vertical section. Fig. 3 is a horizontal section on the line 3—3 of Fig. 2. Fig. 4 is a similar section on the line 4—4 of Fig. 2.

Referring more particularly to the drawing, 1 represents a suitable base which is provided with a circular head 2 having a ratchet upper face 3 and a central screw threaded bore 4. Threaded into the bore 4 is a main jack screw 5 which has slidably mounted thereon a locking nut or member 6 having a ratchet undersurface 7 to coact with the ratchet surface 3 of the head 2. This locking nut or collar 6 is provided with an internal gib or key 8 which is seated in the longitudinal groove 9 formed in the screw so as to cause the locking nut to rotate with the main jack screw 5. When the jack screw 5 is rotated in the proper direction to unscrew it from the base 1, the lock nut 6 will rotate with the screw and ride up upon the same to disengage its ratchet teeth from the teeth 3.

The upper end of the screw 5 is provided with a circular ratchet head 10 and the screw is hollowed out and threaded so as to receive the auxiliary jack screw 11. The head 10 is provided with ratchet teeth 12 arranged in position to the teeth 13 and adapted to be engaged by ratchet teeth 13 arranged in position to the ratchet teeth 7 and carried by the auxiliary locking collar 14 which is slidably mounted upon the auxiliary screw 11. This collar is also provided with an internal gib or key 15 which engages the longitudinal channel or groove 16 so as to cause the lock nut 14 to rotate with the screw 11 and yet permit the same to slide vertically on the

screw 11. The upper portion of the screw 11 has secured thereto a head 17 upon which is rotatably mounted the abutment or rest 18. The head is provided with a plurality of apertures 19 which are adapted to receive the operating lever 20. It will be noticed that the screw 5 and the screw 11 are oppositely threaded, as shown, the screw 5 being provided with a right hand thread and the screw 11 being provided with a left hand thread. This order may be reversed if found to be desirable. The locking nuts 6 and 14 are provided with set screws 21 which are adapted to hold the locking collars in elevated position upon the screws so that these screws may be backed into their respective holders.

In operating the device, if the lever 20 be forced away from the spectator the screw 5 will be unscrewed from the base 1, the lock nut 6 riding idly over the head 2 and the lock nut 14 positively engaging the head 10 to rotate the screw. Upon movement of the lever in the opposite direction, the lock nut 6 will lock with the head 2 while the lock nut 14 will ride idly over the head 10 and the screw 11 will unscrew from the bore in the screw 5. To lower the screws into their respective holders, it is only necessary to slide the lock in its vertical groove upon the screws and hold them in elevated positions by means of the set screws 21.

What is claimed is:-

1. In combination, a base, a screw threaded into the base, a second screw threaded into the first screw, a lever connected to the second screw, and means to alternately and automatically lock one screw and permit the rotation of the other screw upon a reciprocating movement of the lever.

2. In combination, a base, a screw threaded thereto, a second screw threaded into the first screw and having its threads running in opposite directions to the threads of the first screw, a lever connected to the second screw, and opposite ratchet connections between the first screw and the base and between the second screw and the first screw.

In testimony whereof I affix my signature in presence of two witnesses.

JOHN CORYELL.
